UNITED STATES PATENT OFFICE.

BURTON S. AIKMAN, OF MILWAUKEE, WISCONSIN, ASSIGNOR TO NATIONAL BRAKE & ELECTRIC COMPANY, OF MILWAUKEE, WISCONSIN, A CORPORATION OF WISCONSIN.

PUMP AND PUMPING SYSTEM.

1,423,291.

Specification of Letters Patent. Patented July 18, 1922.

Application filed September 16, 1915. Serial No. 50,941.

To all whom it may concern:

Be it known that I, BURTON S. AIKMAN, a citizen of the United States, residing at Milwaukee, in the county of Milwaukee and 5 State of Wisconsin, have invented a certain new and useful Improvement in Pumps and Pumping Systems, of which the following is a full, clear, concise, and exact description, reference being had to the accompanying drawings, forming a part of this specification.

10 My invention relates to pumps and pumping systems and contemplates an improved apparatus which may be employed as an isolated plant for furnishing water to a residence or an industrial establishment from a nearby source, such as a well.

15 It is the purpose of my invention to provide an improved system which supplies water "fresh from the well," that is without the intervention of a storage or reserve tank, and which will be under "faucet control," by which I mean that the flow of water is controlled by the acts of opening and closing 20 the faucets which form the supply outlets of the system.

25 To supply water fresh from the well and to maintain the flow of water under faucet control is, broadly speaking, a matter of prior art. The apparatus and systems heretofore known and used were, however, subject to inherent difficulties due to the fact 30 that their mode of operation required complexities such as alternately operating chambers, valves operated by marginal differences 35 in pressure or by time element devices, and to the fact that the pneumatic control employed led to frequent misoperations such as are commonly called "blow-overs" where 40 the system becomes cleared of water and the compressed air, employed as an operating medium, is wasted.

45 According to my invention there is provided a single water chamber alternately subject to air pressure and relieved therefrom, the alternations being secured by the 50 actuations of valve mechanism which, in turn, are directly and mechanically dependent upon the rise and fall of the water in the chamber. So far as I am aware, I am the first to provide a faucet controlled water system depending upon a single cylinder pump for supplying the water. It will be understood that the system is constantly 55 under pressure and it is therefore a further

object of my invention to provide an apparatus which will be as free from leaks as possible, which operates with a minimum consumption of air and which operates reliably and positively. The last mentioned 60 characteristic is due to the direct relation of the valve mechanism to the water levels, whereby the movement of the valve is dependent upon the physical change which requires such movement, and I provide means 65 for causing sudden actuations of the valve mechanism notwithstanding the fact that the rise and fall of the water in the chamber is comparatively gradual.

70 My invention is illustrated in the accompanying drawings in which—

Figure 1 is a more or less diagrammatic view illustrating the system as a whole;

Figure 2 is a plan view of the pump;

75 Figure 3 is a vertical axial sectional view taken on the plane of the line 3, 3, of Fig. 2 and looking in the direction indicated by the arrows;

Figure 4 is a vertical axial sectional view taken on the plane of the line 4, 4, of Fig. 80 3 and looking in the direction indicated by the arrows;

Figure 5 is a vertical axial partial sectional view taken on the plane of the line 5, 5, of Fig. 2 and looking in the direction 85 indicated by the arrows;

Figure 6 is a partial sectional view, similar to a portion of Fig. 3, but drawn on a larger scale, and

Figure 7 is an isolated view taken on the 90 plane of the line 7, 7, of Fig. 3 and looking in the direction indicated by the arrows.

Referring first to Fig. 1, which, as before stated, is diagrammatic, it will be seen that the well tubing or casing is illustrated at 8, 95 the water level being indicated at 9. The pump structure, which I have indicated broadly by the reference character 10, is disposed in the well at a suitable distance below the water level therein, as will be described. The pump structure has leading therefrom three pipes, an air pressure pipe 11, an exhaust pipe 12, and a water discharge pipe 13. The air pressure pipe 11 is connected with a compressed air tank 14, 100 in which air is compressed by means of a compressor 15, operated, for instance, by an electric motor 16. It will be clear to those skilled in the art that the compressor 15 may be operated by any suitable means such 110

as a gas engine or steam engine, and if desired means may be provided for automatically starting and stopping the prime mover dependent upon the fall and rise of pressure in the tank 14. In the pipe 11 the cut-off valve 11^a, air strainer 11^b, reducing valve 11^c, gauge 11^d, and drain cock 11^e are provided.

The water discharge pipe 13 leads to various branch pipes 17 and 18, each of which, in turn, leads to an outlet faucet 19. By means of a pipe 20, the discharge pipe 13 is connected with a chamber 21, closed except for the entry pipe 20, for a purpose which will be pointed out presently.

It will now be understood that this system represents an isolated plant for installation in a residence, for instance. The water discharge pipe leads from the well, conveniently near by, to the distribution pipe in the building, and the compressor, motor, compressed air tank and chamber are suitably housed in any convenient way.

As before pointed out, air pressure is constantly maintained upon the system. It is therefore necessary to maintain a certain pressure between predetermined minimum and maximum limits in the compressed air tank 14, this being done by the proper starting and stopping of the compressor 15, either manually or automatically. It has been my experience that, a proper compressed air tank being provided, it is necessary in employing a distribution system for an ordinary residence, for instance, merely to operate the compressor intermittently, say every two or three days, for a short time, in order to keep the pressure in the compressed air tank within the desired limits.

It will appear as this description proceeds that with the pressure properly maintained upon the system, everything is at rest so long as all the outlet faucets of the system are closed, but as soon as one of them is opened the pumping mechanism will operate to maintain continuous the flow which immediately commences. When the faucet is again closed the apparatus comes to rest and it will appear that the feed has been direct from the well with the proper pressure to distribute it to whatever points desired.

I refer now to Figs. 2 to 7, inclusive, to describe the pumping mechanism. A head member 22 and a primary base member 23, both of circular form, are joined by a cylindrical housing 24 which forms a water chamber 25. As illustrated in Fig. 4, the head member 22, and the primary base member 23 are tied together by means of two pipes 26, 26, which thread into the head member 22 and pass through openings in the primary base member 23, the lower ends of these pipes being screw-threaded for the

reception of nuts 27, 27 which, when tightened, clamp the housing 24 firmly in place to form a water-tight and air-tight compartment. Secured to the under side of the primary base member 23, by means of screws 28, 28, is the secondary base member 29 which has extending downwardly therefrom a central boss 30 to which a foot 31 is screw-threaded, a conical screen 32 being clamped between the foot 31 and the boss 30, and thus held against the under side of the secondary base member 29. The secondary base member 29 is provided with two water inlet openings 33, 33, each of which is controlled by a valve 34 hinged, by means of a link 35, at 36 to a standard 37 extending upwardly from the base.

The primary base member 23 is provided with an axial opening 38 in which the lower end of a vertically reciprocating cylinder 39 is slidably mounted. The lower end of this cylinder is open, as shown, and openings 40, 40, are provided in the side walls thereof. It will be seen that the cylinder 39 is so constructed that a shoulder 41 is formed therein, below the openings 40, 40, and this shoulder forms a valve seat to be engaged by the ball float valve 42 which is confined within the cylinder 39. As shown in Fig. 3, the top of the cylinder 39 is closed. This need be so only so far as the proper retention of the ball float valve 42 is concerned. This reciprocating cylinder 39 forms a hollow piston working in the short cylinder bearing 38 and constitutes a motor member for actuating the admission and exhaust valves.

Extending upwardly from the top 43 of the cylinder 39 is a stem 44 which extends upwardly to a point near the head member 22. As shown, the stem 44 terminates at its upper end in a spider which comprises the radial members 45, 45, and the annulus 46.

The head member 22 is provided with the atmosphere passageway 47, the compressed air inlet passageways 48 and 49, the primary water chambers 50 and the secondary water chamber 51. These passageways and chambers are isolated from each other, as will be described, the atmosphere passageway being connected with the pipe 12, the compressed air inlet passageway 48 being connected with the pipe 11, and the secondary water chamber 51 being connected with the discharge pipe 13.

Referring now first to the atmosphere passageway 47 it will be seen that it is so fashioned as to lead to the axial opening 52 in the bottom of the head 22, a valve seat 53 surrounding this opening. The lift valve 54 having a compressible face 55 co-operates with the valve seat 53 to open and close the exhaust port 52, the valve being mounted upon an extension 56 from stem 44 and having a lost motion connection with the ex-

tension 56 of the stem 44 and being held against the seat 53 by the difference in pressure between the pump chamber and the outside thereof, during the interval of lost motion 5 of the stem 44 after the member 45 is moved away from the under side of valve 54 and before the shoulder 57 comes in contact with the valve face. The extension 56 is provided with shoulder 57, which 10 after certain movement of motor piston 39, engages the face of the exhaust valve 55, so that further movement of motor piston 39 and stem 44 breaks the exhaust valve loose from its seat against the pressure within the 15 chamber. The extension 56 is also provided with enlargement 58 which rides in the sleeve 59, set axially in the head 22 and disposed concentrically in the opening 52. A helical spring 60 is confined in the sleeve 59 20 between the enlargement 58 and the face of the valve 54 for the purpose of imparting a quick movement to the valve 54 after it has been broken loose from the seat by the shoulder 57. This quick movement is imparted to 25 valve 54 by spring 60 for the purpose of securing a wide opening of the valve 54 quickly so that there will be no obstruction to the out-rush of pressure fluid from the cylinder, and so that the flow of air outwardly will 30 not be able to draw the valve 54 back upon its seat.

The two compressed air inlet passageways 48 and 49 are connected by a port 61 which has a valve seat 62 surrounding the upper 35 end thereof, this valve seat co-operating with a valve 63, having a compressible face 64. The valve 63 is carried upon a supplemental stem 65 which, in turn, engages in a central pocket 66 in the upper end of the extension 40 56. The lower end of the supplemental stem 65 is adapted to be engaged by the bottom 45 of the pocket 66, as shown in Fig. 3, and also, in Fig. 6, and a spring 67 is provided to maintain the lower end of the supplemental 50 stem out of such engagement. The valve 63 is set in a pocket 68 axially in the top of the head 22, this pocket being closed by a plug 69. The valve 63 is provided with peripheral grooves 70 in order to balance 55 the pressure on opposite sides of the valve when it is in open position, it being understood that the compressed air comes in through the passageway 48.

A ring 71 is secured to the outside of the 55 cylinder 39 and this ring forms a shoulder between which and the ring 72 on the primary base member 23 the helical spring 73 is disposed, this spring thus having a tendency to move the cylinder 39 and the parts 60 connected therewith upwardly. Consequently, unless some means prevents it, the spring 73, in moving the stem 44 upwardly causes the annulus 46 of the spider at the top of the stem to engage the under side of 65 the valve 54 and holds that valve on its seat

so as to cut off communication between the water chamber 25 and the atmosphere, until valve 63 is opened and pressure admitted to the chamber 25, after which the difference in pressure between the pump chamber and the outside thereof holds valve 54 tightly against the seat 53, as it is not necessary that spring 73 be strong enough to do more than close valve 54 and open valve 63. The difference of pressure between the chamber 25 70 and the outside thereof holds valve 54 to the seat 53 until valve 54 is engaged by the shoulder 57 on the extension of the stem 44 during the downward movement of stem 44. By the same action the valve 63 will be lifted 75 from its seat 62, due to the engagement of the bottom of the supplementary stem 65 with the bottom of the pocket 66, and, once lifted from its seat, the valve 63 is balanced 80 and will then naturally rise further under 85 the influence of the spring 67. In this condition the apparatus affords a free passage for the compressed air through the passageways 48, 61 and 49 so that the compressed air is exerted on the surface of the water 90 contained in the chamber as will hereinafter more fully be pointed out.

The water which is in the chamber 25 is forced out of that chamber under the influence of the compressed air, through the 95 openings 40, 40 in the cylinder 39 and downwardly out of the bottom of the cylinder into the compartment between the primary base member 23 and the secondary base member 29. The lower ends of the pipes 100 26, 26, communicate with this compartment by means of the openings 74, 74, in the nuts 27, 27, the interior of these nuts communicating directly with the interiors of the pipes 26, 26.

As the water is thus gradually forced out of the chamber 25 the ball float valve 42 will gradually drop with the level of the water until that valve rests upon the valve seat 41. It will be obvious, then, since the cylinder 39 110 is capable of downward movement, and since the float valve 42 has now closed the bottom thereof, that the continued application of the compressed air will result in downward movement of the cylinder 39 and the parts 115 connected therewith. In order to facilitate this downward movement, I provide means whereby the pressure below the movable cylinder 39 may be released. This means is in the form of a valve 75 which controls the 120 water outlet passageway 76. This valve 75 is normally held closed by a spring 77 mounted upon a stud 78 in the foot 31, this entire arrangement being disposed in the pocket 79 formed centrally in the boss 30. The pocket 79 has the vent 80 and it will 125 now be seen that if the valve 75 is moved downwardly it will permit the exit of water from the compartment below the movable cylinder 39, by way of the passageway 76, 130

pocket 79, and vent 80. The lower end of the cylinder 39 carries a spider 81 which forms a buffer 82 disposed in axial alignment with the stem of the valve 75. When the cylinder 39 comes down this buffer engages the valve to open it, as will be clear from inspection of Figures 3 and 4.

The opening in the motor piston 110 is closed by the valve 42 while the line of the water is still above the seat 41. This secures a water seal of all the joints and valves of the motor so that no air is driven over into the water pipes even though leakage past the piston or valve may occur during the pressure stroke of the motor. In the same manner the motor is submerged during the exhaust stroke of the same. The exhaust stroke of the motor is made as will be explained later, when the pump cylinder 25 is filled with water and when the float 93 releases the detent or trigger 86. This relation permits the cylinder to be filled with maximum speed and without waste of water from the operation of the motor.

The water seal, which is always maintained between the motor and the air in the pumping chamber is particularly important in a faucet controlled system because such a system is under constant pressure and subject to leakage and moreover the faucets may be suddenly or gradually opened or closed at any stage of the operation of the pump or of the parts of the pump.

In the downward movement of the cylinder 39 the rod 44 removes the spider 45 and annulus 46 from the back of the valve 54 and begins to compress the spring 60 against the face of the valve 54, which is being held against the seat 53 by the difference of pressure within the pump chamber and the outside thereof. Further movement of the rod 44 permits valve 63 to seat, thus the supply of compressed air is cut off before the valve 54 is opened by the shoulder 57 on the continuation of the rod 44. Then valve 54 moves downwardly to open passageway 52 and the movement of the valve after it leaves seat 53 is accelerated by the recoil of spring 60. Thus the compressed air is cut off and immediately thereafter the chamber 25 is openly connected with the atmosphere.

It will be seen from Figure 1 that the inlet at the bottom of the pump structure, which is covered by the screen 32, is considerably below the level of the water in the well and there will therefore be this head of water tending to open the valves 34, it being assumed that whatever passes inwardly through the vent 80 is negligible. Since there is merely atmospheric pressure within the chamber 25, the opening of the valves 34, 34, will admit water from the well into the chamber above them, by way of the openings 33, 33, and the ball float valve 42 will be lifted from its seat so as to admit water into

the water chamber 25, the float valve rising as the water rises.

It is now pertinent to consider another action which takes place. Secured to the under side of the head 22 is a bracket frame 181 which has the downward extensions 182, 182, and 83. Mounted upon shaft 84 which turns in the downward extensions 182, 182, as best illustrated in Figures 3 and 7, is an arm 85 to which a trigger 86 is pivoted at 87, the trigger being otherwise supported by means of a swinging fork 88 pivoted at 89 to the extension 83. Also mounted upon the shaft 84 is an arm 90 which, as illustrated in Fig. 7, extends around the spider to the other side of the axis of the chamber. The arm 90 swings with the arm 85 and in order to secure this operation it is convenient to secure both arms to the shaft 84, the axis of which is the pivotal axis. Hung from the free end 85 of arm 90, at pivot 91 is a rod 92 to which a float 93 is secured, this float depending in a float box 94 carried near the upper end of the chamber 25 upon the pipes 26, 26, by means of a bracket 95. At the bottom of 90 this float box an outlet 96 is provided and this outlet is controlled by a flap valve 97 pivoted at 98 in the bracket 95, an arm 99 swinging with the valve in the nature of a bell-crank lever, and being adapted to be 95 engaged by a collar 100 on the stem 44, as will hereinafter be pointed out. A spring 97 tends to hold the valve closed.

Around the annulus 46 of the spider which is provided at the top of the stem 44 a bearing ring 101 is provided, this bearing ring having a shoulder 102. When the stem is in its uppermost position, as illustrated in Figure 3, the end of the trigger 86 bears against the outside of the ring 101 below the shoulder 102, the weight of the float 93 tending to hold it in this position, it being assumed as will hereinafter be pointed out, that under these circumstances there is no water in the float box 94 to hold the float in its uppermost position. When the stem 44 is brought into its lowermost position, however, the trigger, due to the weight of the float 93, is moved toward the center of the spider and consequently catches over the shoulder 102, thus latching the stem 44 and the parts connected therewith in their lowermost position. When unlatching takes place the stem 44 moves upwardly and among the other operations which have been described the collar 100 engages the arm 99 to open the valve 97, thus permitting the exit of water from the float box 94 by way of the opening 96.

During the expulsion of the water from 125 the chamber 25 the flow is secured out of the chamber at the bottom and upwardly through the pipes 26, 26, into the primary water chambers 50. The pressure forces the water past the check valves 103, 103, by way 130

of the opening 104, 104, into the secondary water chamber 51 from which the discharge pipe 13 leads. The check valves 103, 103 are each held seated by means of the spring 105, held under a plug cap 106 screwed into the top of the head member 22.

Although in this description the isolated operation of the various parts has been referred to to facilitate a clear understanding 10 of the structure, I shall now give a brief, but connected description of the complete operation. Let it be assumed, by reference to Fig. 3, that the apparatus is now in such condition that water is being forced from the 15 chamber 25. As indicated, the chamber has been partly emptied and the stem 44 is in its uppermost position. In this condition the chamber 25 is closed off from the atmosphere, since the valve 54 is closed, and compressed air finds its way down through the 20 passageway 48, port 61 and passageway 49, since the valve 63 is open. Under these conditions the trigger rests upon the ring 101 below the shoulder 102, the valve 97 is open, 25 the valves 34, 34, are closed and the valves 103 are open. It will be seen that the water which has collected in the chamber 25 will therefore be forced downwardly, through the openings 40 to the interior of the cylinder 39, down through the cylinder, out the bottom thereof, through the ports 74, 74, upwardly through the pipes 26, 26, into the primary water chambers 50, 50, through the 30 openings 104, 104, into the secondary water chamber 51, and out through the discharge pipe 13 to the distribution pipes 17 and 18 and faucets 19. Under these circumstances, 35 reference to Figure 1 will show that water will also be forced into the air chamber 21, confining an air cushion above the water 40 level formed therein, as indicated in dotted lines. As the level of the water in the chamber 25 is lowered, it runs out of the float box 94 by way of the passageway 96, 45 and the ball valve 42 is maintained in its uppermost position within the cylinder 39 until the water level comes down far enough, after which the float valve will gradually drop with the water. The apparatus is now 50 feeding the system under the pressure of the compressed air tank 14, it being assumed that one or more of the faucets 19 are open. If all the outlets of the distribution system are closed, everything will be at rest since, 55 although there is pressure on the top of the water in the chamber 25, there is no outlet for the water. Let it be assumed now that the withdrawal of water from the system is continued. The water in the chamber 25 60 continues to drop, the float valve 42 going down with the water until it reaches the seat 41. This, as before described, closes off the outlet from the chamber 25 and the feed of water ceases. The opening in the hollow 65 motor member 39 is closed by the valve 42

as the water level descends, while the motor member is completely submerged. Thus a water seal is maintained between the air in the chamber 25 and the motor to prevent leakage at the valve seat 41 and the bearing 70 38. However, since the pressure is continued, and since the cylinder 39 and the parts connected therewith are capable of downward movement, the continued pressure moves the cylinder 39, and its associated 75 parts, downwardly. The valve 75 is promptly opened to relieve the pressure below the cylinder 39 and to permit the continued movement of the cylinder. Since the weight of the float 93 tends to move the trigger 86 80 85 toward the center of the spider, it will be clear that when the downward movement of the cylinder 39, stem 44, and the associated parts, has taken place to a sufficient extent, the trigger will pass over the shoulder 102 to hold the movable structure in its lowermost position. This downward movement is performed quickly and during the movement the compressed air is first cut off by the closure of the valve 63 and the atmosphere 90 passage is opened by the opening of the valve 54. When the air in the cylinder 25 is released by opening of the exhaust valve 54, the motor is still submerged in the water trapped in the bottom of the chamber 25 so that a water seal is maintained at 95 all times between the air in the chamber and the motor. Also, during this movement, the arm 99 is released from the collar 100 to permit the valve 97 to close. As before pointed out, an immediate inrush of water from the well follows. The valves 34, 34, open to permit this entry of water and the float valve 42 is lifted off its seat and permits the passage of the water into the chamber 25. Since 100 the valve 97 is closed, the water cannot enter the float box from below, but must rise to the level of the top of the float box, as indicated by the dot-and-dash line. Once up to this level, the water suddenly pours into 105 the float box 94 and the float 93 rises to withdraw the trigger 96 from contact with the shoulder 102, whereupon under the influence of the spring 73 the entire movable structure, comprising the cylinder 39, stem 110 44, and associated parts, starts upwardly, executing the exhaust stroke of the motor. During this stroke of the motor a water seal is maintained between the air at atmospheric 115 pressure in the cylinder 25 and the motor. This upward movement causes the spider to engage the under side of the valve 54, closing that valve, and also causes the bottom of the pocket 66 to engage the bottom of the supplementary stem 65 to raise the valve 63 120 from its seat. Thus, the atmosphere is shut off and the compressed air is again admitted to the chamber. Then follows again the steady expulsion of the water from the 125 chamber. In the operation wherein the wa- 130

ter rises the valve 97 is closed and in the operation where the water falls the valve is held open as described.

The speed with which the chamber 25 fills 5 to the upper level of course depends upon the sizes of the inlet passageways and the head of the water in the well. I have made experiments which show that with a structure built substantially along the lines of 10 that illustrated in the drawings, and substantially of these proportions, submerged about ten feet below the level of the water in the well, a period of about 1.5 seconds is required for the filling operation. If the 15 capacity of the discharge and distribution pipes is great enough, this momentary cessation of pressure will be hardly perceptible at the faucets, particularly since the expulsion period, assuming one or more faucets to be 20 open for a considerable length of time, consumes practically all the time. However, in order that the gap in the flow may be properly filled in, I provide the air chamber 21 to which the pipe 20 delivers from the discharge pipe 13. Obviously, when the water 25 in the discharge pipe 13 is under pressure, as it is practically all of the time, a certain amount of water is forced up into the chamber 21. This action compresses the air in the chamber and forms a cushion which is maintained so long as the pressure is not relieved. As soon as the pressure is relieved, 30 however, by the cessation of pressure in the pump with a faucet open, the air is given opportunity to expand and in doing so forces out the water which has become packed 35 therein and provides a flow from the faucet during the refilling period of the pump. This chamber 21 will, of course, be distinguished from a storage tank, since all it does 40 is to increase the capacity of the system and provides means for a certain amount of compression to be released for a very short period, about 1.5 seconds, at a time. It will be 45 understood that this water which is in the chamber 21 is directly a part of the discharge system being located in effect directly between the well and the faucet, and the small consignment of water is constantly being changed. In this way, a continuous flow 50 from the faucet is insured. I have found by experiment that the air in the chamber 21 is kept properly replenished by bubbles of air which follow the expulsion of water from the water chamber 25 of the pump structure and that it is automatically relieved from 55 an excess of air by the opening of a faucet, this latter action being instantaneous and imperceptible to the opening of the faucet.

60 As before pointed out, during this refilling operation, the cylinder 39 of the pump structure and the parts associated therewith are in their lowermost position, being held by the trigger 86. When the level of the 65 water reaches the top of the box 94, the

water flows suddenly into the box, raises the float 93, releases the trigger 86, and permits the movable structure to move to its upward position to reverse the valve to close off the atmosphere and admit the compressed air, 70 whereupon the cycle of operations which have been described will be repeated. The cylinder 39 with its adjuncts forms a pressure operated motor for operating the main pump valve. The motor is controlled by 75 the low level condition in the pump through the agency of the float valve 42. It is controlled by the high level condition of the water in the pump by means of the float 93 and the connected trigger mechanism 86. 80

Having thus described the normal operation of the pump, I will describe the condition under which many failures have occurred when air displacement pumps are controlled by the faucet with the air pressure on the pump at all times. In supplying water for domestic service there are long intervals during which no water at all is used. The most frequent of these is the period over night, and in many instances during this period, a very minute quantity of water is used 90 on account of slight leaks in the plumbing fixtures, or because some faucet is not closed absolutely tight. This causes water in pump chamber 25 to move down very slowly, and 95 it will be seen that there must be a quick positive exhaust and refilling of the chamber 25 regardless of the length of time required for the water in the chamber to reach the tripping point, at which the valve mechanism operates. In my invention this is provided for by the lost motion connection referred to between rod 44 and the valve 54, and the lost motion connection between the bracket frame 81 and the valve 75. For it 100 will be seen that no matter how slowly valve 42 applies movement to the pressure motor 110, there will be no opening of the valve 54 until the movement has been great enough to bring the shoulder 57 into contact with 105 the face of valve 54, before which bracket frame 81 comes in contact with the valve 75 and opens it. This permits exit of the water from the compartment below the movable cylinder 39 to pass into the well from the 110 passage 76, pocket 79 and vent 80. By this venting of passageway 76 a quick movement of the pressure motor 110 is obtained insuring a positive and quick opening of valve 54, so that a quick reversal of the operating 115 valves is obtained, which insures a prompt refilling of the pump chamber regardless of the speed at which liquid is discharged from the chamber. 120

It will be seen that the upper and lower 125 levels of the water in the chamber 25 positively determine the reversal of the valves. The atmosphere condition is maintained until the upper level reaches the top of the float box and the compressed air condition 130

is maintained until the level has dropped to the point of seating the float valve 42. In this way the reversal of the valves is mechanically dependent upon the conditions which require their reversal and there is thus secured a positive and reliable operation not subject to the defects pointed out in the early part of this description.

It will be seen that the reversal of the valves is sudden, as has been described, and that the arrangement is such that at no time is there even an effective connection between the compressed air and the atmosphere. I find that this is essential for commercial operation of the pump and to the end of securing these results the lost motion connection between the rod 44 and the valve 54 is essential in the construction which I have illustrated. It will be clear that suction instead of full atmosphere may be applied to the pipe 12 without departing from the spirit and scope of my invention.

I have endeavored to embody the features of my invention in a simple structure involving a minimum number of parts of simple design, and some of the more limited of the appended claims are directed to these more specific features.

I claim:

1. In a pump, the combination of a single chamber having inlet and outlet valves for the admission and expulsion of liquid, two ports, one for exhaust and one from a source of motive fluid, a mechanically connected valve structure for alternately closing one of said ports and opening the other, means moved by pressure of the motive fluid for opening the exhaust port and closing the compressed air port, and valve means lying within the chamber and controlled by the rise of liquid in said chamber for controlling the pressure operated means for closing the exhaust port and opening the port for motive fluid.

2. In a pump, the combination of a chamber having inlet and outlet valves for the admission and expulsion of liquid, two ports, one for exhaust and one from a source of compressed air, a valve structure for alternately closing one of said ports and opening the other, means moved by air pressure for opening the exhaust port and closing the compressed air port, and resilient means for closing the exhaust port and opening the compressed air port.

3. In a pump, the combination of a chamber having inlet and outlet valves for the admission and expulsion of liquid, two ports, one for exhaust and one from a source of compressed air, a valve structure for alternately closing one of said ports and opening the other, means moved by air pressure for opening the exhaust port and closing the compressed air port, and resilient means for closing the exhaust port and opening the

compressed air port, both of said means being directly controlled by the level of the liquid in said chamber.

4. In a pump, the combination of a chamber having inlet and outlet valves for the admission and expulsion of liquid, an atmosphere port and a compressed air port, a valve for alternately closing one of said ports and opening the other, a movable member connected with said valve, said member tending to move to one of its positions, said member being moved to its opposite position by compressed air, a latch for holding said member in said latter position, and float mechanism for releasing said latch.

5. In a pump, the combination of a chamber having inlet and outlet valves for the admission and expulsion of liquid, an atmosphere port and a compressed air port, a valve for alternately closing one of said ports and opening the other, a movable member connected with said valve, said member tending to move to one of its positions, said member being moved to its opposite position by compressed air, a valve which when the liquid has reached its minimum level halts the expulsion from said chamber, the compressed air thereafter being exerted to move said movable member, a latch for holding said member in said latter position, and float mechanism for releasing said latch.

6. In a pump, the combination of a chamber having inlet and outlet valves for the admission and expulsion of liquid, an atmosphere port and a compressed air port, a valve for alternately closing one of said ports and opening the other, a movable member connected with said valve, said member tending to move to one of its positions, said member being moved to its opposite position by compressed air, a latch for holding said member in said latter position and float mechanism for releasing said latch, said float mechanism operating in a box which the liquid enters when the maximum level has been reached.

7. In a pump, the combination of a chamber having inlet and outlet valves for the admission and expulsion of liquid, an atmosphere port and a compressed air port, a valve for alternately closing one of said ports and opening the other, a movable member connected with said valve, said member tending to move to one of its positions, said member being moved to its opposite position by compressed air, a valve which when the liquid has reached its minimum level halts the expulsion from said chamber, the compressed air thereafter being exerted to move said movable member, a latch for holding said member in said latter position, and float mechanism for releasing said latch, said float mechanism operating in a box which the liquid enters when the maximum level has been reached.

8. In a pump, the combination of a chamber having inlet and outlet valves for the admission and expulsion of liquid, an atmosphere port and a compressed air port, a valve for alternately closing one of said ports and opening the other, a movable member connected with said valve, said member tending to move to one of its positions, said member being moved to its opposite position by compressed air, a valve which when the liquid has reached its minimum level halts the expulsion from said chamber, the compressed air thereafter being exerted to move said movable member, a latch for holding said member in said latter position, and float mechanism for releasing said latch, said float mechanism operating in a box which the liquid enters when the maximum level has been reached, said box being permitted to empty with the fall of the liquid in the chamber.

9. In a pump, the combination of a liquid chamber, a discharge chamber normally connected therewith, said discharge chamber having inlet and outlet check valves, an exhaust port and an air pressure port for said chamber, a valve, movable means for operating said valve, a spring tending to hold said means in position to close the exhaust port and open the pressure port, said means being moved to its reverse position by air pressure but the air pressure being ineffective thereon while the connection between said chambers is open, means for closing said connection, a latch for holding the movable means in its reverse position, and float mechanism for releasing said latch.

10. In a pump, the combination of a liquid chamber, a discharge chamber normally connected therewith, said discharge chamber having inlet and outlet check valves, an exhaust port and an air pressure port for said chamber, a valve, movable means for operating said valve, a spring tending to hold said means in position to close the exhaust port and open the pressure port, said means being moved to its reverse position by air pressure but the air pressure being ineffective thereon while the connection between said chambers is open, a float valve for closing said connection, a latch for holding the movable means in its reverse position and float mechanism for releasing said latch.

11. In a pump, the combination of a liquid chamber, a discharge chamber normally connected therewith, said discharge chamber having inlet and outlet check valves, an exhaust port and an air pressure port for said chamber, a valve, movable means for operating said valve, a spring tending to hold said means in position to close the exhaust port and open the pressure port, said means being moved to its reverse position by

air pressure but the air pressure being ineffective thereon while the connection between said chambers is open, means for closing said connection, a latch for holding the movable means in its reverse position, and float mechanism for releasing said latch, said float mechanism operating in a box located within and near the top of said chamber, said box receiving the liquid from the top thereof and being provided with a check valve to permit the exit of the water near the bottom thereof.

12. In a pump, the combination of a liquid chamber, a discharge chamber normally connected therewith, said discharge chamber having inlet and outlet check valves, an exhaust port and an air pressure port for said chamber, a valve for each port, movable means for simultaneously operating said valves, a spring tending to hold said means in position to close the exhaust port and open the pressure port, said means being moved to its reverse position by air pressure but the air pressure being ineffective thereon while the connection between said chambers is open, means for closing said connection, a latch for holding the movable means in its reverse position, and float mechanism for releasing said latch.

13. In a pump, the combination of a liquid chamber, a discharge chamber normally connected therewith, said discharge chamber having inlet and outlet check valves, an exhaust port and an air pressure port for said chamber, a valve for each port, movable means for simultaneously operating said valves, the valves being approximately balanced when unseated, a spring tending to hold said means in position to close the exhaust port and open the pressure port, said means being moved to its reverse position by air pressure but the air pressure being ineffective thereon while the connection between said chambers is open, means for closing said connection, a latch for holding the movable means in its reverse position, and float mechanism for releasing said latch.

14. In a pump, the combination of a liquid chamber, a discharge chamber normally connected therewith, said discharge chamber having inlet and outlet check valves, an exhaust port and an air pressure port for said chamber, a valve, movable means for operating said valve, a spring tending to hold said means in position to first close the exhaust port and then open the pressure port, said means being moved to its reverse position by air pressure but the air pressure being ineffective thereon while the connection between said chamber is open, means for closing said connection, a latch for holding the movable means in its reverse position, and float mechanism for releasing said latch.

15. In a pump, the combination of a liquid

- chamber, a discharge chamber normally connected therewith, said discharge chamber having inlet and outlet check valves, an exhaust port and an air pressure port for said liquid chamber, a valve, movable means for operating said valve, a spring tending to hold said means in position to close the exhaust port and open the pressure port, said means being moved to its reverse position by air pressure but the air pressure against the pressure in said discharge chamber being ineffective on said means while the connection between said chambers is open, means for closing said connection, a latch for holding the movable means in its reverse position, and float mechanism for releasing said latch.
16. In a pump, the combination of a liquid chamber, a discharge chamber normally connected therewith, said discharge chamber having inlet and outlet check valves, an exhaust port and an air pressure port for said chamber, a valve, movable means for operating said valve, a spring tending to hold said means in position to close the exhaust port and open the pressure port, said means being moved to its reverse position by air pressure but the air pressure against the pressure in said discharge chamber being ineffective on said means while the connection between said chambers is open, means for closing said connection, means for relieving the pressure in said discharge chamber, a latch for holding the movable means in its reverse position, and float mechanism for releasing said latch.
17. In a pump, the combination of a head and a base, a cylinder between them, pipes tying said head and base together, exhaust and pressure ports in said head, a valve mechanism for controlling said ports, a liquid inlet valve in said base, and a liquid outlet valve in said head, the liquid in the chamber formed by said cylinder being discharged through said base, through said pipes and past said outlet valves in said head.
18. In a pump, the combination of a head and a base, a cylinder between them, pipes tying said head and base together, exhaust and pressure ports in said head, a valve for controlling said ports, liquid inlet valves in said base, liquid outlet valves in said head, the liquid in the chamber formed by said cylinder being discharged through said base, through said pipes and past said outlet valves in said head, float mechanism controlling the movement of said first named valve, and a float box in which said mechanism operates supported within said cylinder upon said pipes.
19. In a pump, a chamber having inlet and outlet valves for the inlet and expulsion of liquid, two ports, one for exhaust, and one for the admission of motive fluid, a motor for controlling both of the motive fluid ports, said motor having a piston moved by pressure of the motive fluid for opening the exhaust port and closing the admission port, and means disposed within the chamber and controlled by the rise of liquid in said chamber for closing the exhaust port and opening the admission port.
20. In a pump, the combination of a water chamber and a discharge chamber separated by a partition, inlet and outlet valves for said discharge chamber, air inlet and outlet valves for said water chamber, a cylinder through which water may pass mounted for vertical movement in said partition, a valve seat in said cylinder, a float valve confined in said cylinder, means connecting said cylinder and said air valves and a spring tending to move said cylinder in one direction, the cylinder being moved in the opposite direction by air pressure.
21. In a pump, the combination of a water chamber and a discharge chamber separated by a partition, inlet and outlet valves for said discharge chamber, air inlet and outlet valves for said water chamber, a cylinder through which water may pass mounted for vertical movement in said partition, a valve seat in said cylinder, a float valve confined in said cylinder, means connecting said cylinder and said air valves, a spring tending to move said cylinder in one direction, the cylinder being moved in the opposite direction by air pressure, and a vent valve for said discharge chamber opened by the latter movement of said cylinder.
22. In a pump, a chamber having inlet and outlet valves for the inlet and expulsion of liquid, two ports, one for exhaust, and one for the admission of motive fluid, valves for said ports, a motor for operating both of said valves, said motor having a piston moved by pressure of the motive fluid for changing the condition in said chamber from a pressure condition to an exhaust condition, and means disposed within the chamber and controlled by the rise of liquid in said chamber and controlling the motor for changing the condition in said chamber from an exhaust condition to a pressure condition.
23. In a pump, a chamber having inlet and outlet valves for the inlet and expulsion of liquid, two ports, one for exhaust, and one for the admission of motive fluid, a valve structure for alternately closing one of said ports and opening the other, a motor for operating said valve structure, the motor having a piston moved by pressure of the motive fluid for moving the valve structure to open the exhaust port and close the admission port, and means disposed within the chamber for closing the exhaust port and opening the admission port.
24. In a pump, a chamber having inlet and outlet valves for the inlet and expulsion of motive fluid, a motor

of liquid, two ports, one for exhaust, and one for the admission of motive fluid, a mechanically connected valve structure for alternately closing one of said ports and opening the other, means moved by pressure of the motive fluid for opening the exhaust port and closing the admission port, and means for closing the exhaust port and opening the admission port, said latter means being disposed wholly within the chamber, both of said means being directly controlled by the level of the liquid in said chamber.

25. In a pump, the combination of a chamber having inlet and outlet valves for the admission and expulsion of liquid, an atmosphere port and a compressed air port, a valve for alternately closing one of said ports and opening the other, a movable member connected with said valve, said member tending to move to one of its positions, said member being moved to its opposite position by compressed air, a latch for holding said member in said latter position, float mechanism for releasing said latch, a discharge 25 pipe leading from said liquid outlet valves, and a faucet in said discharge pipe.

26. In combination, a pump barrel, liquid inlet and outlet ports, an exhaust port, an admission port for motive fluid, mechanically connected valve means for alternately closing one of the air ports and opening the other, means controlled by emptying of the barrel and actuated by pressure of the motive fluid for closing the admission port and opening the exhaust port, and means disposed within the barrel and controlled by filling of the barrel for closing the exhaust port and opening the admission port.

27. In a pump, the combination of an admission valve for motive fluid and an exhaust valve, a lost motion connection between said valves, a pressure motor operated by the pressure of the motive fluid for operating said valves, and level controlled devices for governing said pressure motor.

28. In a pump, the combination of admission and exhaust ports having valves, a pressure motor for alternately opening one and closing the other of said valves, a high level float for controlling the motor to close the exhaust port and open the admission port, and a low level float controlling the motor to close the admission port and thereafter open the exhaust port.

29. In a pump, the combination of admission and exhaust valves, a pressure operated motor for alternately opening one and closing the other valve, a water box having inlet at the top and outlet at the bottom and a level controlled device in said box for controlling said pressure motor.

30. In a pump, a pumping chamber, the combination of admission and exhaust valve means, a pressure motor operated by the pressure of the motive fluid for operating

said valve means, float means governed by high water level and by low water level in the pump for controlling the operation of the motor to operate said valve means to exhaust the pressure in the pump in response to low water conditions and to admit pressure in response to high water conditions in the pump, said float means having guiding means wholly disposed within said pumping chamber. 75

31. In a pump, the combination of a liquid chamber having inlet and outlet means, an exhaust passageway, a pressure medium passageway, a pressure motor operated by the motive fluid, valve mechanism operated by said pressure motor to control the connection of said chamber alternately with said passageways, and means wholly enclosed within the chamber and governed by the liquid level in the chamber controlling the 80 operation of said pressure motor.

32. In a pump, the combination of a barrel, a head member for the barrel having an inlet passageway, an exhaust passageway, an intermediate passageway communicating 90 with the barrel of the pump, a substantially axial opening connecting said passageways, a valve between the inlet and intermediate passageways, a valve between the exhaust and intermediate passageways, and means 95 connecting said valves.

33. In a pump, the combination of a barrel, a head member for the barrel having an inlet passageway, an exhaust passageway, an intermediate passageway communicating 100 with the barrel of the pump, a substantially axial opening connecting said passageways, a valve between the inlet and intermediate passageways, a valve between the exhaust and intermediate passageways, and means 105 connecting said valves, and level controlled means governing the actuation of said connecting means.

34. In combination, a pump barrel having a head member, an admission passageway, 110 an exhaust passageway, and an intermediate passageway between them, a transverse opening connecting all of said passageways, an admission valve for closing off the admission passageways, an exhaust valve for closing off the exhaust passageway, and an operating stem having a lost motion connection with each of said valves, said stem projecting through said transverse opening. 115

35. In a pump, the combination of a barrel, having a head member, an admission passageway, an exhaust passageway, and an intermediate passageway between them, a transverse opening connecting all of said passageways, an admission valve for closing off the admission passageway, an exhaust valve for closing off the exhaust passageway, a motor device for operating said valves, said motor device having lost motion connection with each of said valves. 125 130

36. In a pump, the combination of a barrel, a head member having admission and exhaust passageways, and an intermediate passageway between them, a transverse opening connecting said passageways, an admission valve closing off the admission passageway, an exhaust valve for closing off the exhaust passageway, said admission valve having a stem and an operating stem 5 projecting through the exhaust valve, and adapted to engage the stem of the admission valve.
37. In a pump, the combination of a barrel, a head member for the barrel, said head member having admission and exhaust passageways, and an intermediate passageway between them, a transverse opening connecting said passageways, an admission valve closing off the admission passageway, an exhaust valve for closing off the exhaust passageway, an operating stem having lost motion connection with the valves and an annular sleeve about said stem, said sleeve being seated in a wall of the exhaust passage to 10 form a double annular seat for the exhaust valve.
38. In combination, a pump barrel, a head member for the barrel, said head member having formed therein an admission passageway, an exhaust passageway and an intermediate passageway lying between said passageways and communicating with the pump barrel, an admission valve for controlling the connection between the admission passageway and said intermediate passageway, and an exhaust valve for controlling the connection of the exhaust passageway with the pump barrel, and spring means for holding the exhaust valve closed and 15 the admission valve open.
39. In combination, a pump barrel, a head member for the barrel, said head member comprising an admission passageway, an exhaust passageway and an intermediate passageway lying between said passageways and communicating with the pump barrel, an admission valve for controlling the connection between the admission passageway and said intermediate passageway, an exhaust 20 valve for controlling the connection between said exhaust passageway and said pump barrel, spring means for holding the exhaust valve closed and the admission valve open, and motor means controlled by the level of liquid in the pump for overcoming said spring means.
40. In a pump, the combination of a barrel, a head member having admission and exhaust passageways and an intermediate passageway between them, said intermediate passageway communicating with the barrel of the pump, a transverse opening connecting all of said passageways, admission and exhaust valves for closing off the admission passageway from said intermediate passageway and said exhaust passageway from said pump barrel, respectively, said valves having connecting means lying in said transverse opening, said head member having water passageways substantially 70 on opposite sides of the transverse passageway and check valves in said head for said water passageways.
41. In a pump, the combination of a cylindrical barrel, a head member having admission and exhaust passageways and an intermediate passageway between them communicating with the interior of the barrel, an axial transverse opening connecting all of said passageways, admission and exhaust valves for closing off the admission passageway from the intermediate passageway and the exhaust passageway from the barrel, said valves having connecting means lying in said transverse opening, a foot 75 member for the barrel, water passageways in said head member upon opposite sides of the axial transverse opening, and tie pipes between the head and the foot member communicating with said water passageways. 80
42. In a pump, the combination of admission and exhaust valves, a pressure motor having a movable pressure operated element for operating said valves, level control means governing the application of pressure to said element, a fluid chamber on the remote side of said element, and a relief valve for relieving fluid pressure on said remote side, said relief valve being operated by the initial movement of the element 90 to impart a snap motion to said admission and exhaust valves, all of said valves being of lift type. 95
43. In a pump, the combination of a main barrel comprising a piece of tubing, a head member closing the upper end of said barrel, a foot member closing the lower end of said barrel, said head member having means for alternately admitting and exhausting motive fluid, a discharge passage in said head member, a tie pipe connected between the head and foot member and serving as means for conducting water from the bottom of the barrel into the water passage in the head and an inlet check valve for the foot member 105 for filling the barrel. 110
44. In a pump, the combination, of a chamber having inlet and outlet valves for liquid, an admission port for motive fluid, an exhaust port, a valve structure for alternately closing one of said ports and opening the other, means moved by pressure of the motive fluid for opening the exhaust port and closing the admission port and resilient means governing admission of the motive 115 fluid. 120
45. In a pump, the combination of a chamber having inlet and outlet valves for liquid, two ports, one for exhaust and one for admission of the motive fluid, a valve 130

- structure for alternately closing one of said ports and opening the other, a pressure motor operated by the pressure of the motive fluid on the outward stroke for opening the 5 exhaust port and closing the compressed air port, and spring means for making the return stroke of the motor.
46. In a pump, the combination of a single pumping chamber having inlet and outlet 10 valves for liquid, two ports, one for exhaust and one for the admission of motive fluid, mechanically connected valve means for both of said ports, motor means controlled by the fall of the level of the liquid 15 and moved by pressure of the motive fluid for changing the condition in said chamber from a pressure condition to an exhaust condition, said means comprising a floating ball valve.
47. In a pump, the combination of a chamber having inlet and outlet valves for liquid, two ports, one for exhaust and one for the admission of motive fluid, mechanically connected valve means for both of said 20 ports, motor means controlled by fall of the level of the liquid and moved by pressure of the motive fluid for changing the condition in said chamber from a pressure condition to an exhaust condition, said means comprising a float valve disposed within 25 the chamber, and means controlled by the rise of liquid in said chamber for changing the condition in said chamber from an exhaust condition to a pressure condition, said 30 means comprising a float and engaging means movable therewith disposed within the casing.
48. In a single cylinder pump of the class described, the combination of exhaust and 40 admission ports for motive fluid, main valves for said ports, a float valve disposed within the cylinder, a pressure motor operated by the motive fluid and controlled by the float valve for operation of one of said main 45 valves, the exhaust of the motor being controlled by the main exhaust valve.
49. In a pump, the combination of a single pumping chamber, a main admission valve for admitting motive fluid, a main exhaust 50 valve, a pressure motor operated by pressure of the motive fluid for operating said valves, and valve means disposed within the chamber and controlled by the level of the 55 liquid in the pumping chamber for governing said pressure motor.
50. In a pump, the combination of a single pumping chamber, a main admission valve for motive fluid, a main exhaust valve, a pressure motor operated by the pressure of 60 motive fluid for operating said main valves, a valve port for the pressure motor disposed within the said chamber, and a level controlled device governing the valve port to control the application of pressure to said 65 motor.
51. In a pump, the combination of a pumping chamber, admission and exhaust valves, a pressure operated motor controlling the alternate opening of one and closing of the other valve, and a level controlled device 70 having all of its connected parts disposed within said chamber controlled by high level of liquid in the pump governing said pressure motor.
52. In a pump, the combination of a single 75 working cylinder, admission and exhaust valves, a pressure operated motor for opening the exhaust valves and closing the inlet valve, level controlled means governing the closing of the exhaust valve and opening of 80 the inlet valve, and a level controlled device having all its operating parts disposed within the chamber governing the application of pressure to the motor.
53. In a pump, the combination of a barrel, a head member for the barrel having an admission passageway, an exhaust passageway, an intermediate passageway communicating with the barrel of the pump, said intermediate and said admission passageways 90 being adapted to communicate with each other, a valve between the admission and intermediate passageways, a valve for the exhaust passageway, and pressure operated motor means within the barrel controlling 95 the operation of said valves.
54. In a pump, the combination of a barrel, a head member for the barrel having an admission passageway, an exhaust passageway, and an intermediate passageway, 100 said intermediate passageway leading to the barrel and adapted to communicate with the admission passageway, an admission valve between the admission and intermediate passageways, an exhaust valve between the 105 pump barrel and the exhaust passageway, a valve stem connecting said valves and projecting through all three of said passageways, and a pressure motor within the barrel connected to said stem and controlling the 110 operation of said valves.
55. In a pump, the combination of a barrel having a head member, an admission passageway, an exhaust passageway, and an intermediate passageway between them, an admission valve for closing off the admission passageway, an exhaust valve for closing off the exhaust passageway, and a motor device 115 for operating said valves, said motor device having lost motion connection with the exhaust valve.
56. A pump comprising the combination of a chamber having inlet and discharge means, admission and exhaust valves, a plurality of level controlled devices having their 120 connected operating parts disposed within the chamber, a motor for opening the exhaust valve and closing the admission valve, one of said level controlled devices being responsive to control application of pressure 125 to said

to the motor at low level, and another of said level controlled devices governing closing of the exhaust valve and opening of the admission valve.

5 57. A pump comprising the combination of a chamber having inlet and discharge means, an admission valve for admitting motive fluid, and an exhaust valve, said admission and exhaust valves being mechanically interconnected by a movable connection, a pair of level controlled devices enclosed in said chamber, a motor for operating the valve structure to open the exhaust valve and close the admission valve, one of 10 15 20 25 30 35 40 45 50 55 60 65 70 75 80 85 90 95 100 105 110 115 120 125 130

15 said level controlled devices being responsive to low level to control application of pressure to the motor, and the other of said devices governing said valve structure to close the exhaust valve and open the admission valve.

58. In a pump, the combination of a single liquid chamber having liquid inlet and outlet means, admission and exhaust valves, a pressure motor for operating the said valves, 25 a valve port for the pressure motor and a float governing said pressure motor valve port, said port and float being disposed within the said chamber.

59. In a pump, the combination of a single liquid chamber having liquid inlet and outlet means, admission and exhaust valves, a pressure motor for operating the said valves, a motor valve port governing the application of pressure to the pressure motor and 30 35 40 45 50 55 60 65 70 75 80 85 90 95 100 105 110 115 120 125 130

60. In a pump, the combination of a pumping chamber, admission and exhaust ports, having valves, a pressure motor for operating said valves, a high level float for controlling the closing of the exhaust valve and opening of the admission valve, and a low level float controlling the motor to open the exhaust port and close the admission port, said floats operating through means disposed wholly within the chamber.

61. In a pump, the combination of a water chamber and a discharge chamber separated by a partition, inlet and outlet valves for said discharge chamber, air inlet and outlet valves for said water chamber, a cylinder through which water may pass, mounted for vertical movement in said partition, a valve seat in said cylinder, a float valve confined in said cylinder, means connected to said cylinder adapted to engage the outlet valve for the water chamber, the cylinder being moved in one direction by air pressure, a spring tending to move said cylinder in the opposite direction, and a vent valve for said discharge chamber, opened by movement of said cylinder.

62. In a pump, the combination of a

single pumping chamber having inlet and outlet valves for the inlet and expulsion of liquid, two ports, one for exhaust and one from a source of motive fluid, facing lift valves connected together and adapted to alternately close and open to admit and exhaust motive fluid to and from the chamber, a pressure motor actuated by the motive fluid governing the opening of the exhaust valve and the closing of the admission valve.

63. In a pump, the combination of a pump having valves for admission and expulsion of liquid, a single water chamber and a discharge chamber separated by a partition, air inlet and outlet valves for said water chamber, a cylinder through which water may pass, mounted for vertical movement with respect to said partition, a valve seat in said cylinder, a float valve for said seat confined in said cylinder, said cylinder having means governing the opening of the exhaust valve and closing of the air inlet valve.

64. In a pump, the combination of a chamber having inlet and discharge means, admission and exhaust valve means, a pressure motor for operating said valve means, said motor being actuated at the time that the chamber is to be exhausted by a fluid pressure on one stroke and having means for storing energy on the outward stroke for making the return stroke.

65. In a pump, the combination of a chamber having inlet and discharge means for liquid, admission and exhaust valves for motive fluid, a pressure motor for operating said valves, said motor being actuated by pressure of the motive fluid to actuate the valves, and to store energy for its own return stroke, and level controlled means within the pump governing the application of pressure to said motor.

66. In a pump, the combination of a chamber having inlet and discharge means for liquid, admission and exhaust valves for motive fluid, a pressure motor for operating said valves, said motor being actuated by pressure of the motive fluid, at the time that the chamber is to be exhausted, to open the exhaust valve and close the admission valve, spring means compressed by the outward stroke of the motor for making the return stroke of the motor and level controlled means governing the closing of the exhaust valve and opening of the admission valve.

67. In a pump, the combination of a chamber having inlet and discharge means for liquid, admission and exhaust valves for motive fluid, said valves having a mechanical connection between them, a pressure motor for operating said valves, said motor being actuated at the time that the chamber is to be exhausted by pressure of the motive fluid to open the exhaust valve and close the admission valve and spring means compressed

by the outward stroke of the motor for making the return stroke of the motor.

68. In a pump, the combination of a chamber having inlet and discharge means for liquid, admission and exhaust valves for motive fluid, a pressure motor for operating said valves, said motor being actuated by pressure of the motive fluid at the time that the chamber is to be exhausted, to open the 10 exhaust valve and close the admission valve, level controlled means governed by low level for controlling the application of pressure to said motor and high level means controlling the closing of the exhaust valve and 15 opening of the admission valve, said level controlled means transmitting motion to means disposed wholly within the casing.

69. In a pump, the combination of a pumping chamber, main inlet and discharge 20 valves for liquid, main admission and exhaust valves for motive fluid, a pressure motor controlling said admission and exhaust valves, and a floating valve governing the application of pressure to the motor, said 25 floating valve being controlled by low level conditions in the liquid chamber.

70. In a pump, a single working chamber having main inlet and discharge valves for liquid, main admission and exhaust valves 30 for motive fluid, a pressure motor for operating said admission and exhaust valves, said motor having a port therethrough for discharging liquid from the working chamber to the main discharge valve, and a floating 35 valve governed by low level conditions in the working chamber controlling the application of pressure to the pressure motor.

71. In a device of the class described, the combination of a single pumping chamber, 40 inlet and discharge valves for liquid, admission and exhaust ports for admitting and exhausting motive fluid, valve means controlling said ports, a pressure motor device adapted to be operated by pressure of the 45 motive fluid, said pressure motor comprising a cage, a floating ball valve in said cage, an outlet for liquid through said cage controlled by the floating ball valve and means governing the opening of the main exhaust valve 50 operated by said motor.

72. In a pump, the combination of a single working cylinder, admission and exhaust valve means for motive fluid, a motor device governing said valve means, said motor device comprising a movable member having an outlet for the discharge of liquid from the working cylinder, and a floating 55 ball valve adapted to obstruct the discharge outlet and cause movement of the motor device to cause exhaust of the motive fluid.

73. In a pump, the combination of a chamber having inlet and discharge valves for liquid, admission and exhaust valves for motive fluid, a pressure motor for controlling 60 the operation of the valves, said motor

being adapted to have communication with the liquid in the pumping chamber, a low level valve controlling the application of pressure to the motor, said pressure being transmitted to a portion of the liquid and a 70 relief port for accelerating the motor on one stroke, and spring means operating on the motor tending to open the admission valve and close the exhaust valve.

74. In a pump, the combination of a 75 pumping chamber having inlet and discharge valves for liquid, admission and exhaust valves for motive fluid, a pressure motor operated by the pressure of the motive fluid for controlling the operation of 80 the admission and exhaust valves, said motor being adapted to have communication with the liquid in the pumping chamber, a low level valve for controlling the application of pressure to the motor and means whereby 85 a portion of the discharging liquid is discharged into the well for the purpose of preventing a slow movement of said motor and spring means operating on the motor and tending to open the admission valve 90 and close the exhaust valve.

75. In a pump, the combination of a pumping chamber having inlet and discharge valves for liquid, admission and exhaust valves for motive fluid, a pressure 95 motor for controlling the operation of the admission and exhaust valves, said pump being organized to have a lost motion connection between the motor and the exhaust valve, a level controlled valve controlling 100 application of pressure of the motive fluid to the pressure motor, means for discharging a portion of the liquid from the pump to accelerate the stroke of the motor, and spring means operating on the motor and tending 105 to open the admission valve and close the exhaust valve.

76. In a pump, the combination of a pumping chamber having inlet and discharge valves for liquid, admission and exhaust valves for motive fluid, a pressure motor for controlling the operation of the admission and exhaust valves, a low level controlled valve for controlling the application of pressure to the motor while a body of 110 liquid in the pump is in communication with the discharge pipe, and means for permitting the escape of a portion of said liquid externally of the discharge port, and spring means operating on the motor and tending 115 to open the admission valve and close the exhaust valve.

77. In a pump, the combination of a pumping chamber having inlet and discharge check valves, admission and exhaust 125 ports for motive fluid, a motor for controlling said admission and exhaust valves, a low level controlled valve for controlling the application of pressure to the motor while a body of liquid remains between the 130

5 pump chamber and the discharge check valve, means for permitting a portion of said body of liquid to escape when the water in the chamber has reached a predetermined level, and spring means for opposing one stroke of the motor.

78. In a pump, the combination of inlet and discharge valves for liquid, admission and exhaust valves for motive fluid, a pressure operated motor for operating said admission and exhaust valves, a controlled valve controlling application of pressure to the motor, means for permitting pressure to escape from the motor and a spring compressed on one stroke of the motor.

79. In a pump, the combination of a single pumping chamber having inlet and discharge valves for the liquid, admission and exhaust ports for motive fluid, valve mechanism governing said ports, a pressure operated motor operated by pressure of the motive fluid transmitted through a portion of the liquid, said valve mechanism being operated by said motor on one stroke and means energized by the one stroke of the motor for making the return stroke of the same.

80. In a pump, the combination of a single pumping chamber having inlet and discharge valves for liquid, admission and exhaust ports for the admission and exhaust of motive fluid to and from the pumping chamber, a motor operated by pressure of the motive fluid in the pumping chamber, said pressure being transmitted through a portion of the liquid, valve mechanism for governing the admission and exhaust ports, said valve mechanism being operated by said motor on one stroke of the motor, and means energized by the one stroke of the motor for making the return stroke of the same.

81. In a pump, the combination of a single pumping chamber having inlet and discharge valves for liquid, admission and exhaust port means for motive fluid, a pressure motor operated on one stroke by pressure of the motive fluid transmitted through a portion of the liquid at each stroke, valve means operated by said pressure motor governing the admission and exhaust port means and means independent of pressure of the motive fluid for making the return stroke of the motor.

82. In a pump, the combination of a pumping chamber, inlet and discharge valves for liquid, admission and exhaust valves for motive fluid, a pressure motor controlling said admission and exhaust valves, a float valve governing the application of pressure to the motor, said float valve being controlled by low level conditions in the liquid chamber and means for discharging a portion of the liquid from the pump, said low level float valve being carried down

below the point of initial application of pressure to the motor when said motor starts to move.

83. In combination, a single pumping cylinder, a head member, a foot member attached to said cylinder, a movable piston in said cylinder, an admission and an exhaust valve in the head of the cylinder and a relief valve in the foot member, said valve being operated by movement of the piston.

84. In combination, a pump cylinder, a head member, a foot member attached to said pump cylinder, motor means having a movable piston in said cylinder, an admission and an exhaust valve in the head of the cylinder, a relief valve in the foot member, connecting means for connecting said piston with all of said valves, said connection means having lost motion therein.

85. In a pump, the combination of a single pumping chamber having inlet and discharge valves for liquid, admission and exhaust valves for fluid pressure, a pressure motor for controlling the operation of said admission and exhaust valves, said pressure motor having a motor chamber, said motor chamber having an opening to the outside to permit of the relief of pressure in said motor chamber, a float valve in the pumping chamber governing the application of pressure to said pressure motor, said float valve being controlled by the low level conditions in the pumping chamber.

86. In a pump, the combination of a single pumping chamber having inlet and discharge valves for liquid, admission and exhaust valves for fluid pressure, a pressure motor for controlling the operation of said admission and exhaust valves, said pressure motor having a motor chamber, a relief port in said motor chamber, and a float valve disposed within the pumping chamber governing the application of pressure to said pressure motor, said float valve being controlled by low level conditions in the liquid chamber.

87. A pump embodying a chamber having a liquid inlet, a pressure fluid inlet, a pressure fluid outlet and a liquid outlet, the liquid outlet including a cylinder, a piston for the cylinder, a valve seatable against the piston for closing the liquid outlet when the liquid level is lowered a predetermined amount, a valve for the pressure fluid outlet, spring means for throwing the pressure fluid outlet valve open when said piston is moved by pressure within said chamber, and a passage communicating with said chamber and the atmosphere, and a valve for closing said passage and operated by the piston to move open when the piston starts to move, to instantly relieve pressure in the cylinder.

88. A pump embodying a chamber having a liquid inlet and outlet and a pressure fluid inlet and outlet, the liquid outlet including

a cylinder, a piston working in said cylinder, a valve cooperable with said piston for closing the liquid outlet when the liquid level lowers a predetermined amount in said 5 chamber, a valve for closing the pressure fluid outlet, means operated by the piston for unseating the second mentioned valve when the piston is moved by pressure fluid in said chamber, a relief passage having one 10 end extending away from and communicating with said cylinder and its other end leading to the exterior of the pump, and a valve for normally closing the first-mentioned end of said relief passage and moved to open position away from said passage when said 15 piston is moved.

89. A pump embodying a chamber having a liquid inlet, a pressure fluid inlet and outlet, a member having a liquid outlet and a 20 cylinder communicating therewith, a piston working in said cylinder, a valve cooperable with said piston to close the liquid outlet when the liquid level lowers a predetermined amount, a valve for closing the pressure fluid outlet, means for unseating the second 25 mentioned valve when the piston is moved, said member having a relief passage having one end extending away from and communicating with the cylinder and its other end leading to the exterior of the pump, and a valve disposed below the piston for normally 30 closing the first-mentioned end of said passage and moved to open position when said piston is moved by the pressure fluid in the 35 chamber.

90. A pump embodying a chamber having a liquid inlet, a pressure fluid inlet and outlet, a member having a liquid outlet and a cylinder communicating therewith, a piston working in said cylinder, a valve cooperable 40 with said piston to close the liquid outlet when the liquid level lowers a predetermined amount, a valve for closing the pressure fluid outlet, means for unseating the second 45 mentioned valve when the piston is moved, said member having a boss, and a relief passage extending to the face of the boss and communicating with the exterior of the pump, a cup engaged upon said boss, a stem disposed 50 in line with the piston and projecting through said opening, and a valve carried by said stem seatable against said boss to close said opening and passage.

91. The combination in a pneumatic pump, 55 a cylinder, a depending nipple therein providing an air outlet for the cylinder, a spring pressed member movable within the cylinder and having a valve at one end seatable against the nipple to normally close the passage therethrough, a piston attached to said member and movable within the cylinder, the piston having an opening, and a buoyant valve guided by said member and seatable over the opening of the piston.

92. The combination in a pneumatic pump,

a vertical cylinder having an air outlet passage, a sleeve movable vertically within the cylinder and having openings for the passage of water therethrough, a piston secured to the lower end of the sleeve and working 70 within the cylinder, the piston having an opening, a buoyant valve mounted within the sleeve and seatable over said opening of the piston, a valve carried by the upper end of the sleeve and arranged to close said passage, and means for yieldingly raising the sleeve.

93. The combination in a pneumatic pump, a cylinder, an air outlet passage, a piston working within the cylinder and having an opening, a guide carried by the piston, a buoyant valve guided by said guide and seatable over the opening of the piston, a valve carried by the guide for closing the air outlet passage, and means for yieldingly 85 moving the guide to seat the last mentioned valve.

94. The combination in a pneumatic pump, a cylinder having an air outlet passage, a piston movable within the cylinder 90 and having an opening, a buoyant valve seatable over said opening, a second valve connected to the piston to be moved therewith and operable for closing said passage, and means for yieldably moving the piston 95 to cause the last mentioned valve to normally close said passage.

95. A pump embodying a chamber having a check valved liquid inlet, a pressure fluid inlet, a pressure fluid outlet and a liquid 100 outlet, means operable for automatically closing the pressure fluid outlet when the liquid level rises to a predetermined point in said chamber and adapted to be held in closed position by pressure fluid, and means 105 operable for moving said means to open position out of range of the pressure fluid flowing through the pressure fluid outlet when the liquid has been forced from said chamber through the liquid outlet.

96. A pump embodying a chamber having a check-valved liquid inlet, a pressure fluid inlet and a pressure fluid outlet, a valve for closing the pressure fluid outlet, yielding means having a liquid outlet and adapted to 115 unseat said valve, and means for closing said liquid outlet when the liquid has been forced from the chamber therethrough.

97. A pump embodying a chamber having a check-valved liquid inlet, a pressure fluid 120 inlet, a liquid outlet and a pressure fluid outlet, means for closing the pressure fluid outlet, a movable member having a valve seat through which the liquid flows to the liquid outlet, a buoyant valve seatable upon 125 said seat when the liquid has been forced from the chamber through the liquid outlet, said member being actuated by the pressure fluid when said valve is seated, and said member having means for moving the afore- 130

said means to open position when said member is moved by the pressure fluid.

98. A pump embodying a chamber having a check-valved liquid inlet, a pressure fluid inlet, a liquid outlet and a pressure fluid outlet, a valve for closing the pressure fluid outlet, a pressure fluid operated member having a valve seat through which the liquid flows when forced from the chamber through the liquid outlet, a buoyant valve seatable upon said seat, and means carried by said member for unseating the first-mentioned valve when said member is moved by the pressure fluid.

99. A pump embodying a chamber having a check valved liquid inlet, a pressure fluid inlet, a liquid outlet and a pressure fluid outlet, means for closing the pressure fluid outlet, a member having a cylindrical opening communicating with the liquid outlet and from which the liquid flows to said outlet, a housing having a piston working in said member having a cylindrical opening, valve seats, a valve seatable upwardly against one of said seats, a buoyant valve within the housing seatable downwardly against the other of said seats, said housing when moved by the pressure fluid serving to move the aforesaid means to open position.

100. A pump embodying a chamber having a check-valved liquid inlet, a pressure fluid inlet, a liquid outlet and a pressure fluid outlet, a member having a cylindrical opening communicating with the liquid outlet and from which the liquid flows to said outlet, a housing having a piston working in said member having a cylindrical opening, valve seats, a valve seatable upwardly against one of said seats, a buoyant valve within the housing seatable downwardly upon the other of said seats, and a valve for closing the pressure fluid outlet and unseated when the housing is moved by the pressure fluid.

101. A pump embodying a chamber having a check-valved liquid inlet, a pressure fluid inlet, a liquid outlet and a pressure fluid outlet, a valve for closing the pressure fluid outlet, and means for unseating said valve when the liquid has been forced from the chamber through the liquid outlet, the last mentioned means including spring means adapted to be brought under tension for unseating said valve by a quick movement to throw it from its seat.

102. A pump embodying a chamber having a check-valved liquid inlet, a pressure fluid inlet, a liquid outlet and a pressure fluid outlet, means for closing the pressure fluid outlet, a member through which the liquid flows from the chamber to the liquid outlet, a second member slidably engaging the aforesaid member and having a valve seat, a buoyant valve seatable upon said seat, the second mentioned member being moved by the pressure fluid when said valve

is seated, and the second mentioned member having means for moving the aforesaid means to open position when the second mentioned member is moved by the pressure fluid.

103. A pump embodying a chamber having a check-valved liquid inlet, a pressure fluid inlet, a liquid outlet and a pressure fluid outlet, a valve for closing the pressure fluid outlet, a member through which the liquid flows from the chamber to the liquid outlet, a second member slidably engaging the aforesaid member and having a valve seat, a buoyant valve seatable upon said seat, the second member being moved by the pressure fluid when the second mentioned valve is seated, and spring means movable with the second mentioned member and brought under tension to throw the first mentioned valve from its seat when the second mentioned member is operated by the pressure fluid.

104. A pump embodying a chamber having a check-valved liquid inlet, a pressure fluid inlet and a pressure fluid outlet, yieldable means having a liquid outlet, a valve for automatically closing the pressure fluid outlet when the liquid level rises to a predetermined point in said chamber and adapted to be held in closed position by pressure fluid, a valve for closing the liquid outlet when the liquid level is lowered to a point near the liquid outlet, and means operated by said yieldable means for moving the first mentioned valve to open position out of range of the pressure fluid flowing through the pressure fluid outlet when the second mentioned valve closes the liquid outlet, said yieldable means being movable by pressure fluid when the liquid outlet is closed.

105. In a pneumatic pump, the combination with a pump chamber, provided with water inlet and outlet valves and an air exhaust port, of an air exhaust valve adapted to close the exhaust port when water has filled the pump chamber and adapted to be retained closed by the difference between the pressures in the pump chamber and outside thereof, a compressed air valve, a fluid actuated motor for opening the exhaust valve, and means for casing the motor to open the exhaust valve when the water in the pump chamber has been lowered to a predetermined level.

106. In a pneumatic pump, the combination with a single pump chamber, provided with water inlet and outlet valves, of an air valve and a fluid motor for actuating said air valve, said motor being disposed within the lower part of the pump chamber below the low water level therein for pressure and exhaust so that a water seal will be maintained between the motor and the air in the pump chamber.

107. In combination, a pump cylinder

having a water inlet port, a water discharge port, an air inlet port and an air exhaust port, lift valves for said air ports, and a float valve over the water discharge port for closing the discharge port when the water reaches low level in the cylinder, and means controlled by said float valve for operating said lift valves.

108. In combination, a pump cylinder having a water inlet port, a water discharge port, air inlet port and an air exhaust port, lift valves for said air ports, a float valve over the water discharge port for closing said discharge port when water reaches low level in the cylinder, means controlled by said float valve for operating said lift valves to open the exhaust valve and close the air inlet valve and a high level float controlling said lift valves to permit the exhaust valve 20 to close and the inlet valve to open.

109. In combination, a pump cylinder having a water inlet port, a water discharge port, an air inlet port and an air exhaust port, lift valves for said air ports, a float valve over the water discharge port for closing said discharge port when water reaches low level in the cylinder, means controlled by said float valve for operating said lift valves to open the exhaust valve and close 25 the air inlet valve and a high level float controlling said lift valves to close the exhaust valve and open the air inlet valve, and a lift valve for relieving the pressure below said float valve after the same is seated over the 30 discharge port.

110. In combination, a pump cylinder having a water inlet port, a water discharge port, and air inlet port and an air exhaust port, lift valves for said air ports, a cage 40 over the water the discharge port and a float controlled valve guided by the cage over the water discharge port for closing said port when the water reaches low level, and means controlled by said float valve for operating said lift valves.

111. In combination, a pump cylinder having a water inlet, a water discharge port, an air inlet port and an air exhaust port, a lift valve controlling the air exhaust port 50 and seating with the pressure in the pump cylinder, a float controlled valve for closing the water discharge port when the water reaches low level, and a motor operated by pressure fluid and controlled by the seating of the float controlled valve over the water discharge port for lifting the exhaust valve 55 from its cooperating port.

112. In combination, a single pump barrel, a motor cylinder within the pump barrel, a piston member in said motor cylinder, a head member closing off the top of the pump barrel, a foot member for closing off the bottom of the barrel, a water discharge passageway through the head member, and

a casting closing the lower end of the motor cylinder said casting having an outlet port 65 below the piston and communicating with the water discharge passageway, main valve mechanism for admitting and exhausting air to and from the pump, connections between said main valve mechanism and the piston for causing exhaust in the pump barrel upon low level conditions therein, and a relief passageway through the foot member connected to the motor cylinder below the piston and a relief valve of the 70 lift type operated by the motor piston when the main valve mechanism is actuated.

113. In a pump, the combination of a pair of cylindrical tubes, one within the 80 other, a head member for closing off the tops of both of said tubes, a foot member for closing off the bottoms of both tubes, a discharge passageway through the foot member connecting the lower ends of said tubes, 85 one of said tubes forming a pumping chamber, pressure fluid valve mechanism for the pumping chamber, a movable motor piston operable by pressure in the pumping chamber adapted to be operated upon low level 90 conditions for shifting the pressure valve mechanism, and means for increasing the effective power of said motor piston when it starts to shift the pressure fluid valve mechanism.

114. In combination, a working pump cylinder, an exhaust port, an exhaust valve adapted to be held in seat by the pressure of the motive fluid, a member movable with the water level and having a lost motion connection with said exhaust valve and a spring adapted to be compressed by a part of the downward movement of the member to throw the exhaust valve clear of its seat.

115. In combination, a working pump cylinder, an exhaust port, an exhaust valve adapted to be held on its seat by motive fluid pressure, a piston member adapted to be actuated on low level condition in the pump cylinder, said piston member having 105 a lost motion connection with the exhaust valve, a spring adapted to be compressed by the downward movement of the piston member to throw the exhaust valve clear of its seat and a relief valve for relieving the 110 pressure below the piston member when it starts to compress said spring.

116. In combination, a pump barrel, a motor cylinder within the pump barrel, a piston member for said motor cylinder, a 115 head member closing off the top of the pump barrel, a foot member for closing off the bottom of the barrel, a water discharge passageway through the head member, a casting closing the lower end of the motor cylinder, said casting having an outlet port below the piston and communicating with the water discharge passageway, main valve

mechanism for admitting and exhausting air to and from the pump, connections between the said main valve mechanism and the piston for causing exhaust upon low 5 level condition in the pump barrel, and a relief passageway through the foot member connected to the motor cylinder below said piston and a relief valve operated by the motor piston before the main valve mechanism is actuated.

117. In a pump, the combination of a chamber, a head member therefor having an admission passageway and an exhaust passageway therethrough, a transverse bore between said passageways, said admission passageway having a portion co-axial with said bore and having a valve seat at the end remote from the pump chamber, said exhaust passageway having a portion co-axial with 20 said bore and having a valve seat at the end adjacent the pump chamber, a stem member lying in said transverse bore and facing lift valves cooperating one at a time with said seats.

118. In a pump, the combination of a pumping chamber, level controlled means in the chamber, air valve mechanism for the pump comprising a valve head having an air inlet passageway and an air exhaust passageway, the inner ends of which passageways lead to the pumping chamber, a pair of lift valves facing each other and having stems co-axial with each other and extending toward each other, said passageways having 35 portions extending along the axis of the stems, and valve seats for said valves in said passageways so disposed that the valves when seated are held to seat by fluid pressure, an air motor controlled by said level 40 controlled means for shifting said valves, said motor being adapted to have lost motion with respect to said valves.

119. In a pump, the combination of a pumping chamber, level controlled means in the chamber, air valve mechanism for the pump comprising a valve head having an air inlet passageway and an air exhaust passageway, the inner ends of which passageways lead to the pumping chamber, a 50 transverse opening between said passageways, a pair of lift valves facing each other and having stems co-axial with each other lying in said transverse passageway said inlet and exhaust passageways having each 55 portions extending along the axis of the stems and valve seats for said valves so disposed that the valves when seated are held to seat by fluid pressure and means controlled by said level controlled means for shifting said valves.

120. In a pump, the combination of a pumping chamber, means responsive to level of liquid in the chamber, air valve mechanism for the pump comprising a valve head

having an air inlet passageway and an air 65 exhaust passageway the inner ends of which lead to the pumping chamber, a pair of lift valves facing each other and having stems extending coaxially towards each other, said passageways having each portions extending 70 along the axis of the stems, valve seats in said passageways so disposed that the valves when seated are held to seat by fluid pressure, fluid pressure operated means controlled by said level controlled means for 75 shifting said valves.

121. In a pump, the combination of a pumping chamber, air valve mechanism comprising a valve head having an air inlet passageway and an air exhaust passageway 80 the inner ends of which passageways lead to the pumping chamber, a pair of lift valves facing each other and having stems co-axial with each other and extending towards each other, said passageways having each portions extending along the axis of the stems, valve seats in the passageways for said valves so disposed that the valves when seated are held to seat by fluid pressure and fluid pressure operated means controlled at low 90 level in the pumping chamber to lift the exhaust valve off of seat against the pressure in the pump chamber and to apply the admission valve to seat.

122. In a pump, the combination of a pumping chamber a valve head member having an admission passageway and an exhaust passageway therethrough a transverse bore between said passageways, said admission passageway having a portion co-axial with said bore and having a valve seat at the end remote from the pumping chamber, said exhaust passageway having a portion co-axial with said bore and having a valve seat at the end adjacent the pumping 105 chamber, stems for valves extending into said transverse bore and facing lift valves on said stems cooperating one at a time with said valve seats.

123. In a pump, the combination of a pumping chamber, a valve head member having an admission passageway and an exhaust passageway therethrough a transverse bore between said passageways, said admission passageway having a portion co-axial 110 with said bore and having a valve seat at the end remote from the pumping chamber, said exhaust passageway having a portion co-axial with said bore and having a valve seat at the end adjacent the pumping chamber, stems for valves extending into said transverse bore and facing lift valves on said stems cooperating one at a time with said valve seats, and a pressure operated 115 motor member controlled by level in the 120 chamber for actuating said lift valves.

124. In a pump, the combination of a pumping chamber, a valve head member hav-

- ing an admission passageway and an exhaust passageway therethrough a transverse bore between said passageways, said admission passageway having a portion co-axial 5 with said bore and having a valve seat at the end remote from the pumping chamber, said exhaust passageway having a portion co-axial with said bore and having a valve seat at the end adjacent the pumping chamber, stems for valves extending into said transverse bore and facing lift valves on said stems cooperating one at a time with said valve seats, said exhaust port comprising an annular opening surrounded by a double 10 circular valve seat, the lift valve cooperating therewith comprising a metal backing and a yielding face portion for engaging said double circular valve seat.
125. In a pump, the combination of a 20 pumping chamber, an admission valve and an exhaust valve for air, both of said valves being of the lift type, a fluid pressure motor actuated by a fluid pressure for lifting the exhaust valve from its seat against internal 25 pressure and for applying the admission valve to its seat, and a low level float valve disposed within the chamber for causing operation of the motor to operate said air valves.
126. In a pump, the combination of an 30 admission valve and an exhaust valve for air, both of said valves being of the lift type, a fluid pressure motor actuated by a fluid pressure for lifting the exhaust valve from its seat against internal pressure and for applying the admission valve to its seat, and a low level float valve disposed within the chamber for causing operation of the 35 motor to operate said air valves, said lift valves having a common stem and facing towards each other.
127. In a pump, the combination of an 40 admission valve and an exhaust valve for air, both of said valves being of the lift type, a fluid pressure motor actuated by fluid pressure for lifting the exhaust valve from its seat against internal pressure and for applying the admission valve to its seat, and a low level float valve disposed within the chamber for causing operation of the motor to operate 45 said air valves, said lift valves being axially in line and facing towards each other.
128. In combination, a pumping cylinder, liquid inlet and discharge check valves therefor, a piston fitting in said cylinder, a head member at one end of the cylinder, admission and exhaust ports for motive fluid in the head member, valves for said ports and an operating member for one of said valves 50 comprising a stem having a lost motion connection between the piston and said one valve, and a relief valve operated by said system to deplete the pressure below the pis-
- ton when the expulsion of liquid from the cylinder is substantially completed. 65
129. In a pneumatic pump in combination with a single pumping chamber provided with water inlet and outlet valves of a main air valve and a fluid motor for actuating said air valve, said motor having a control valve 70 which has a seat mounted in the lower part of the pumping chamber below the low water level therein for pressure and exhaust so that a water seal will be maintained between the air in the pump chamber and the seat of 75 said control valve.
130. In combination, a pump having a pumping chamber with the usual liquid inlet and discharge valves, an air port leading from the chamber, said air port serving to 80 permit the pressure from within the chamber to escape, a valve member pressed against the seat by the pressure of the motive fluid within the chamber, said valve member controlling said port, a spring for applying the 85 valve to its seat and a fluid pressure motor for moving the valve from its seat against the pressure of the motive fluid within the chamber, said pressure motor being controlled by low level conditions within the chamber to 90 operate said valve.
131. In a pump, the combination of a 95 pumping chamber, an exhaust valve adapted to seat with internal pressure, a pressure motor having a movable member adapted to move the exhaust valve away from its seat against internal pressure to open the same, said motor having a pressure chamber one 100 side of the member, a relief valve controlled by movement of the member to relieve the pressure in said pressure chamber, and a level controlled valve for controlling the effective application of pressure to said member at low level to cause it to open the relief valve and the exhaust valve. 105
132. In a pump, the combination of a 110 chamber, an exhaust valve, a fluid pressure motor for operating said valve, a low level controlled float valve in the chamber for causing operation of the fluid pressure motor to open the exhaust valve and a high level float mechanism disposed in the chamber for controlling the closing of said exhaust valve.
133. In a pump, the combination of a 115 chamber, a poppet type exhaust valve seating with pressure, a fluid pressure motor for pulling said valve off of its seat and a float controlled valve for the motor disposed within the chamber and adapted upon the 120 low level to control the motor for pulling said exhaust valve off of its seat.
134. In a pump, the combination of a 125 chamber, an exhaust valve, and an admission valve, a connection for said valves, a level controlled means responsive to level

conditions within the chamber, a motor controlled by said means upon low level for opening the exhaust valve and closing the admission valve and mechanical means for holding the admission valve closed and the exhaust valve open until high level in the chamber occurs.

135. In a pump, the combination of a chamber having a head, said head having an admission passageway and an exhaust passageway therethrough, said exhaust passageway leading into the chamber through a valve seat disposed on the bottom of the head and extending therefrom sufficiently to form a valve seat for a lift valve, a lift valve cooperating with said seat to control exhaust of the chamber, said valve seating with the internal pressure of the chamber and a fluid pressure operated motor controlled by low level for lifting said valve away from seat against the internal pressure.

136. In a pump, the combination of a chamber having a head, said head having an admission passageway and an exhaust passageway therethrough, said exhaust passageway leading into the chamber through a valve seat disposed on the bottom of the head, a lift valve cooperating with said seat to control exhaust of the chamber, said valve seating with the internal pressure of the chamber, a fluid pressure operated motor for lifting said valve away from seat against the internal pressure.

137. In a pump, the combination of a pumping chamber, an exhaust passageway, an exhaust valve disposed within said chamber, said valve being a lift valve, a fluid pressure motor for lifting said valve from its seat, and a low level responsive control valve for said motor also enclosed within said chamber.

138. In a pump, the combination of a pumping chamber having a head member and a foot member, air valve means in the head member and water valve means in the foot member, a fluid pressure operated motor, a high level controlled member and a low level controlled member having means moving therewith for controlling the operation of said motor to operate the air valve means, said level controlled members and said means moving therewith being wholly disposed in said chamber.

139. In a pump, the combination of a pumping chamber, connected admission and exhaust lift valves for compressed air, a pressure operated motor for said valves, a high level control for the motor and a low level controlled valve having a controlling port for the motor, said latter valve and port being disposed within the pumping chamber.

140. In a pump, the combination of a pump barrel, a head member for the barrel

having an inlet passageway, an exhaust passageway, a transverse opening connecting said passageways, an inlet valve having its seat at the junction of said inlet passageway and the transverse opening, an exhaust valve having its seat at the junction of the exhaust passageway and transverse opening, said valves having stems lying in said transverse opening and means controlled by the level of liquid in the pump barrel for causing the actuation of said stems and valves.

141. In a pump, the combination of an admission lift valve, an exhaust lift valve, said valves being connected, a fluid pressure motor for lifting the exhaust valve and closing the admission valve, a low level valve governing the application of fluid pressure to the motor and a high level float for controlling the application of a mechanical force independent of fluid pressure to said connected valves to apply the exhaust valve to its seat and to open the admission valve.

142. In a pump, the combination of a cylinder, an exhaust lift valve seating with internal pressure in the cylinder, a fluid pressure motor for lifting said valve from its seat, a low level valve controlling the application of pressure to the motor to cause it to lift said valve to exhaust the cylinder, and a high level float for controlling the application of the exhaust valve to its seat when the cylinder is full of water independently of fluid pressure.

143. In a system of the class described a water distributing system having normally closed outlets, a single cylinder pump comprising an inlet valve of relatively large capacity to permit of rapid filling of the pump with liquid, a discharge valve for liquid, an air admission connection and an air exhaust valve of the lift type seating with internal pressure, said exhaust valve having a relatively large face and cooperating port to permit of rapid exhaust of pressure and rapid filling of the chamber, a fluid pressure operated motor for lifting the exhaust valve away from its seat against the internal pressure, separate high and low level controlled devices for controlling the motor to operate the exhaust valve, and a steady flow chamber of a capacity suitable to supply the flow to said distributing system while the pump is filling.

144. In a system of the class described, a water distributing system having normally closed outlets, a single cylinder pump comprising a liquid inlet valve of a size to permit of rapid filling of the pump with liquid, a suitable discharge valve for liquid, a connection for admitting compressed air, and air exhaust valve of the lift type seating with internal pressure, said exhaust valve having a relatively large port and a cooperating

yielding face to permit of a quick exhaust and rapid filling of the chamber with liquid, a fluid pressure operated motor having its motion accelerated after initial movement 5 for lifting the exhaust valve away from its seat against the internal pressure, means responsive to low level in the cylinder for controlling the effective application of pressure to the motor to open the exhaust valve, and 10 a steady flow chamber of a capacity suitable to supply the flow to the distributing system while the pump is filling.

145. In a single cylinder pump, the combination of a pumping chamber having inlet and discharge check valves for liquid, air control valve mechanism adapted in one position to admit compressed air to the chamber and in another position to exhaust the compressed air from the chamber, a high 20 level float controlling the movement of the air control valve mechanism to admission position, a water box opened at its top and surrounding said float, and a valve at the bottom of said water box, said valve being 25 opened only during the discharge stroke of the pump whereby the water must fill the pumping chamber to the top of the water box before the air control valve mechanism is shifted to admission position.

146. In a single cylinder pump, the combination of a pumping chamber having inlet and discharge check valves, air control valve mechanism comprising admission and exhaust valves of the poppet type, said admission valve seating with the compressed air delivered to the pump, said exhaust valve seating with the pressure in the pump chamber, mechanical means connecting the admission and exhaust valves, a detent for holding 40 said mechanical means in a position to keep the exhaust valve open and the admission valve closed, means tending to move said mechanical means for closing the exhaust valve and opening the admission valve, and 45 a high level float for tripping said detent when the pumping chamber is filled with water.

147. In a single cylinder pump, the combination of a pumping chamber having inlet and discharge check valves, air control valve mechanism adapted in one position to admit compressed air to the chamber and in another position to exhaust the compressed air from the chamber, a high level 55 float controlling movement of the air control valve mechanism to admission position, a water box surrounding said float and having an inlet at its top and an outlet at its bottom, said outlet having means for preventing the entry of water except through the inlet of said box whereby the water 60 must fill the pumping chamber to the inlet of the water box before the air control valve mechanism is shifted to admission position.

148. In a single cylinder pump, the combination of a pumping chamber having inlet and discharge check valves, air controlling valve mechanism adapted in one position to admit compressed air to the chamber and in another position to exhaust the compressed air from the chamber, means for shifting said air controlling valve mechanism from exhaust position to admission position, a latch for holding said means, and a high level float for releasing said latch. 75

149. In a single cylinder pump, the combination of a pumping chamber having inlet and discharge check valves, air controlling valve mechanism adapted in one position to admit compressed air to the chamber and in another position to exhaust the compressed air from the chamber, means for shifting said air controlling valve mechanism from exhaust position to admission position, a latch for holding said means, and a high level float for releasing said latch, a water box surrounding said float and having an admission opening at its top, said box having a discharge opening at the bottom, said discharge opening being opened 90 only during the discharge stroke of the pump whereby the water must fill the pumping chamber to the inlet of the water box before the air control valve mechanism is shifted to admission position. 95

150. In combination, a pumping chamber, check valves for liquid, a connection for compressed air, an exhaust lift valve seating with the internal pressure in the chamber, means in the pumping chamber for pulling said lift valve away from its seat against the internal pressure, and low level means controlling said last named means. 100

151. In a pump, the combination of a pumping chamber, an admission valve of the lift type, an exhaust valve of the lift type, said valves being operable to produce alternately a condition of admission and of exhaust, a float box having an inlet disposed at the top of the chamber and an outlet at 110 bottom of the box, valve means controlling said outlet, a float in said box, means for closing the exhaust valve and opening the admission valve, and a latch for preventing the operating of said last named means, and 115 a connection between said float and said latch for release of the latch when water fills the float box.

152. The combination in a pneumatic pump, a cylinder, a depending nipple there- 120 in providing an air outlet for the cylinder, a spring pressed member movable within the cylinder and having a valve at one end seatable against the nipple to normally close the passage therethrough, a piston attached to said member and movable snugly within the cylinder, the piston having an opening, and a buoyant valve guided by said member 125

and seatable over the opening of the piston.

153. The combination in a pneumatic pump, a vertical cylinder, having an air outlet passage, a sleeve movable vertically within the cylinder and having openings for the passage of water therethrough, a piston secured to the lower end of the sleeve and working snugly within the cylinder, the piston having an opening, a buoyant valve

mounted within the sleeve and seatable over 10 said opening of the piston, a valve carried by the upper end of the sleeve and arranged to close said passage, and means for yieldingly raising the sleeve.

In witness whereof, I hereunto subscribe 15 my name this 13th day of September A. D. 1915.

BURTON S. AIKMAN.
